UNITED STATES PATENT OFFICE.

EVA M. CLEWELL, OF CANTON, OHIO.

CORSET BRACE.

Application filed January 24, 1922. Serial No. 531,392.

The invention relates to an abdominal support or brace having sliding engagement with a corset, so as to be anchored or sustained thereby; and the object of the improvement is to so shape and combine the parts that they can be readily secured and adjusted on the body without inconvenience to the wearer.

The invention is illustrated in the accompanying drawings, forming part hereof, in which—

Figure 1 is a front elevation of the improved corset in position;

Fig. 2, a rear elevation of the same; and

Fig. 3, an open front elevation of the corset, showing the association of the abdominal support therewith.

Similar numerals refer to similar parts throughout the drawings.

The corset 5 may be of any well known form extending upward to or above the waist line and downward around and below the hips, and as shown, may be provided with ordinary lace strings 6 in the rear for adjusting its side sections to the body, and with suitable fasteners 7 and 7' on its forward edges for securing it on the body.

In each side section of the corset is inserted or secured a reinforcing strip 8, in which is provided a series of eyelets 9 extending upward and downward along or near the side of the hips; and on the lower forward side of the corset section is provided a series of loops 10 and 10' as shown in Fig. 1.

The abdominal support 11 may be in the form of a wide oblong band of strong, but flexible, material with a marginal pad 12, of chamois skin or the like, along its lower edge, and a row of eyelets 13 in each end for receiving lacing tapes 14, as shown in Fig. 3.

The lacing tapes 14 extend outward through the eyelets 9 in the sides of the corset, and are passed through corresponding eyelets 15 in the rear end of the cross belts 16, which extend and cross around the back of the body, thence forward around the sides of the hips, whence they are passed through the loops 10 and 10' and are adjustably secured together in the middle of the front, at or near the lower edge of the abdominal support.

The cross belts 16 may be secured by ty-

ing or lacing their ends together, but are preferably fastened together by means of a buckle 17, which may bear upon the pad 12 provided along the lower edge of the abdominal support.

The abdominal support is adjusted to the size of the body by taking up or giving out the lacing tapes 14, after which the corset with the abdominal support associated therewith, may be placed in position by carrying the corset over the head with the abdominal support in front thereof; and after fastening the corset around the body, the cross belts which pass around the back and sides of the body, are drawn up and secured in front thereof with a sufficient tension to clamp the abdominal support across the front of the body to sustain the same as may be desired. In this position the marginal pad along the lower edge of the support not only presses inward and upward across the lower portion of the abdomen, but serves as a bearing for the buckle or other means by which the belts are connected together.

It will be understood that the lacing tapes 14 extend freely through the eyelets 9 at the sides of the corset from front to rear, and are merely guided, aligned and sustained by the corset without using the same as a fulcrum for clamping the pad around the abdomen; so that the bearing for the abdominal support is carried by the cross belts around and across the small of the back and then forward and downward freely through the guide loops, to a point below the middle of the abdomen.

Thus the corset only serves as a sliding and sustaining guide for the lace tapes and body belts of the separate abdominal support, which are placed and secured in clamping position around the corset without interfering in any manner with the free and natural fit of the corset upon the body, while at the same time all the parts are free to adjust themselves in their relative position.

The shoulder brace is in the form of a band 18 extending across the back with straps 19 extending upward and forward over the shoulders and thence rearward under the arms in rear of which they are widened to form side bands 20 for lapping under the ends of the back band in rear of the arm pits.

Reinforcing strips 21 and 22 are provided

- on the ends of the side bands and near the ends of the back bands in which are provided a series of eyelets 23 and 24 through which are passed a series of lace tapes 25; 5 which are carried downward and outward from the eyelets 24 and converge to a connection with a waist strap 26 extending around the side of the body.

- The waist straps 26 are passed through 10 loops 27 and 27' which are provided for that purpose along the upper edge of the front of the corset, whence the straps are secured together in front of the middle of the body, at or near the waist line thereof. 15 The waist straps may be secured by tying or lacing their ends together, but are preferably adjustably secured by means of a buckle 28 as shown in Fig. 1.

- A bust support 29 separate and independent of the shoulder brace, may be worn and is preferably in the form of a band 20 extending across the breast and provided with eyelets in each end through which strings may be laced which may also be laced through the eyelets 23 in the side bands. A separate set of eyelets 23' 25 may be provided in the band so that the lacing and adjustment of the bust support will be entirely independent of the lacing and adjustment of the shoulder brace. The bust support may also have a tape 30 with a

hook or an eye therein for connecting it with one of the corset fasteners in well known manner.

I claim:

1. A corset and the like including eyelets in each side, an abdominal support having lace-tapes on its ends extending through the eyelets and thence rearward around the sides of the corset, and belts extending from the lace-tapes across the back and around the other sides of the corset and adjustably secured together at the front thereof. 35

2. A corset and the like including eyelets in each side and loops on the front of its lower part, an abdominal support having lace-tapes on its ends extending through the eyelets and thence rearward around the sides of the corset, and belts extending from the lace-tapes, across the back and around the sides through the loops on the corset, and adjustably secured together at the front thereof. 45

3. A corset and the like including eyelets in each side, a separate abdominal support 55 having lace-tapes on its ends extending through the eyelets at each side, and tensioning means for the abdominal support cooperating with the lace-tapes extending around the back and also around the front 60 of the corset.

EVA M. CLEWELL.
